GARMENT HANGER SUPPORT

Emmit H. Stephenson, Englewood, Colo.

Application November 1, 1954, Serial No. 32,883

Term of patent 14 years

(Cl. D80—8)

To all whom it may concern:

Be it known that I, Emmit H. Stephenson, a citizen of the United States, residing in the city of Englewood, county of Arapahoe, State of Colorado, have invented a new, original, and ornamental Design for a Garment Hanger Support, of which the following is a specification, reference being had to the accompanying drawing, forming a part thereof.

Fig. 1 is a side elevational view of a garment hanger support showing my new design in closed position.

Fig. 2 is a front elevational view of the same.

Figs. 3 and 4 are top and bottom views, respectively, of the support, on a slightly enlarged scale.

Fig. 5 is a side elevational view of the support, in open or extended position, on a smaller scale than Fig. 1.

I claim:

The ornamental design for a garment hanger support, as shown.
